UNITED STATES PATENT OFFICE.

LOUIS D. DAVIS, OF CARBONDALE, PENNSYLVANIA.

TOOL FOR ATTACHING TIPS TO SHOE STRINGS OR THE LIKE.

Application filed August 16, 1922. Serial No. 582,183.

To all whom it may concern:

Be it known that I, LOUIS D. DAVIS, a citizen of the United States, residing at Carbondale, in the county of Lackawanna and State of Pennsylvania, have invented new and useful Improvements in Tools for Attaching Tips to Shoe Strings or the like, of which the following is a specification.

The present invention relates to tools for attaching tips to cords as to the ends of shoe strings or the like, and has for its objects:

The production of a tool convenient in operation and effective in attaching tips to shoe laces and the like.

Other objects of the invention are simplicity of construction, cheapness of manufacture, and the production of a device having few parts likely to get out of order.

20 Referring to the drawings:

Figure 1 is a perspective view of my device showing the parts thereof in position just preceding the clamping of a tip to a shoe lace.

25 Figure 2 is a plan view and shows the lever members of the device in open position.

Figure 3 is a perspective fragmentary view showing the relation between the jaws of the device and between the cutting apertures.

Figure 4 shows a clip fastened on the end of a shoe string, and;

Figure 5 a clip blank before attachment.

The embodiment of the device as disclosed in the drawing comprises a pair of lever members 10 and 11 formed of comparatively thin flat metallic strips curved toward one end to form operating handles of the type common in pinchers or the like; the opposite ends of the levers being enlarged to form heads 13 and 14. Formed upon the heads are offset portions 15 and 16 through which the pivot pin 17 extends, and one of the heads is formed with a rebent

45 portion 18 which extends in spaced parallelism to the head proper to form a kerf 19. The kerf affords a slideway for the head of the other lever and is preferably rounded at its bottom 20 for the reception of a tip

50 blank as shown in Figure 1, this portion of the head 14 constituting a jaw which may be considered the female jaw of the device, the head of the other arm having its forward edge 21 formed with a groove 22 extending lengthwise thereof, said groove being adapted to cooperate with the rounded

bottom 20 in clamping the tip upon a cord and comprising the male jaw of the tool.

It will be noted by reference to Figure 2 of the drawings and to Figure 1 in connection therewith, that the offset portions 15 and 16 position the pivot 17 in substantial alignment with the space between the bottom 20 and the groove 22 when the jaws are in clamping position. It will also be noted that the offset portions give a comparatively long angular swing of the jaws so that after the male jaw has been brought to approximate clamping position, the further movement of the edge 21 of said jaw will be in substantial parallelism to the bottom 20, whereby the action of the male jaw upon the tip blank will be practically uniform through the length thereof. By this arrangement complicated mechanism for obtaining a parallel movement of one jaw relative to the other during the clamping operation is avoided.

In operation, the tip blank is placed in the bottom 20 of the kerf with the end of a cord resting against its curved inner surface whereupon the male jaw is moved to position riding in the kerf 19. When the male jaw reaches substantially clamping position it will move in substantial parallelism with the bottom of the kerf 20 and will press against the tip blank forcing it into cylindrical form about the cord.

An additional feature of applicant's device is the formation of apertures 23 and 24, countersunk toward the outer surface and adapted to be brought into alignment in one position of the lever members. When in this position a cord may be inserted through the apertures and the countersunk frusto conical surface will act as shears to cut the cord.

It will be seen from the above description taken in connection with the drawings that I have produced a very simple device for attaching tips to shoe strings or the like and yet which accomplishes the purposes ordinarily requiring a more complicated device. I have also been able to reduce the number of parts so as to make a device cheap of manufacture and comprising few parts to get out of order.

What is claimed as new is:—

1. A tool of the character described, comprising a pair of flat levers, having offset portions at their forward ends, a pivot connecting said offset portions, a groove in the

forward end edge of one of said levers, a rebent portion on the forward end of the other lever extending in parallelism thereto and forming a kerf adapted to receive the 6 grooved lever, the bottom of said kerf and said groove lying in radial relation to said pivot and having their longitudinal dimensions lying transversely of the longitudinal dimensions of the levers.

10 - 2. A tool of the character described, comprising a pair of flat lever members having enlarged heads at one end, a groove formed in the forward end edge of one of said heads, the other head having a rebent portion forming a kerf having a rounded bot-

tom, the first named head being slidable in said kerf, said heads having offset portions at one side, a pivot connecting said offset portions, said groove and the bottom of said kerf having their longitudinal dimensions 20 lying in substantially radial relation to said pivot and transversely of the longitudinal dimensions of the levers.

In testimony whereof I have hereunto set my hand in presence of two subscribing 25 witnesses.

LOUIS D. DAVIS.
